UNITED STATES PATENT OFFICE

FRANK M. RINEHARDT, OF BADIN, NORTH CAROLINA

COMBINATION TOILET-RACK

Application filed February 16, 1931. Serial No. 518,285.

The present invention relates to toilet racks and consists in the combinations and arrangements of elements hereinafter described and particularly set forth in the accompanying claims.

The invention has for its purpose to provide a combination toilet rack equipped for holding numerous articles or toilet accessories in such a way that each article is kept in sanitary condition and at proper distance from all the others. The device is proposed with special reference to household or family use wherein there are a number or several toothbrushes and cakes of soap in continuous use over any given period of time. Thus it is intended the toothbrush and soap of each member of the family be kept apart and free from contact with those of the others for obvious sanitary reasons.

A further purpose of the invention is to provide a combined device of this character for conveniently fitting in a bathroom or kitchen, which is inexpensive to produce to the end that the same may be manufactured in large quantities, and at small cost thereby suggesting the same as a convenient article for installation in dwelling houses generally.

The invention is shown by way of illustration in the accompanying drawings, wherein Figure 1 is a perspective view of the combined toilet rack complete.

Figure 2 a top plan view thereof with parts in section.

Figure 3 shows a modified construction of toothbrush receptacle.

Figure 4 is a transverse sectional view on the line 4—4 of Figure 3; and,

Figure 5 shows in section the manner of attaching the shelf to the bar.

Referring to the construction in further detail and wherein like reference characters designate corresponding parts in the different views, the toilet rack consists of a bar 5 having curved end portions 6 which are suitably secured to a base or panel board 7, or the same may be mounted directly on the side wall of the bathroom or other place of installation. Said bar 5 is of that standard construction of design usually known as a towel bar in bathroom fixtures.

A strip or metal sheet 8 shaped to conform with the space between the bar 5 and panel 7 is suitably secured to said panel and bar. The strip has inturned portions 9 that are suitably soldered to the bar as shown in Figure 5. At convenient distances said bar is provided with a plurality of pins or "nails" 10 which project outwardly therefrom as shown and are utilized to engage the cords 11 holding cakes of soap 12. These cakes of soap may obviously be of one kind or variegated, as desired. It is of course understood that these articles are more or less in continuous use in a given time by different persons in the household, or other place, as above set forth.

At each end of the shelf portion 8 there is located a two-part receptacle 13 constructed of sheet metal suitably secured to the shelf and having that off-setting relation shown, and each of said receptacles has its outer end 14 open to receive a toothbrush in the manner indicated. The front and rear portions 15 and 16 respectively of each receptacle are cut-away so that the bristles B of each toothbrush may be exposed to the atmosphere for obvious reasons. The design and location of the respective receptacles are such that the handles of the brushes will project therefrom in the way indicated and the closed end 17 will prevent displacement of the brush in that direction. By thus holding the several toothbrushes on the under side of the shelf 8 said brushes are appreciably kept sanitary and free from dust settling thereon. This also leaves the entire top surface of the shelf for use in holding the usual articles necessary in a bathroom, i. e. toothpaste, shaving mugs, razors, nail files, etc., etc.

Referring to the construction shown in Figures 3 and 4 the toothbrush receptacle 18 is in this instance designed to hold three (3) brushes in proper off-setting relation. Said receptacles are mounted on a plate 19 that is constructed to slidably engage the lugs 20 secured to the shelf portion 8 (see Figure 4). By this removal feature said plate 19 with the several brush holders 18 may be conveniently removed for scalding or other cleaning, as will be understood. In this instance

also the shelf is further provided with hook members 21 for holding soap cakes or other toilet articles.

It will be understood that the invention as herein disclosed is not limited to the details of construction shown and described as these may be varied without departing from the spirit of the invention as defined by the claims.

10 What is claimed as new is:

1. In a toilet rack, the combination of a supporting bar, a shelf mounted on said bar, and devices providing toothbrush receptacles on said shelf, substantially as set forth.

15 2. In a toilet rack, the combination of a supporting bar, a shelf mounted on said bar, and a plurality of sheet metal devices having open ends providing toothbrush receptacles on said shelf, substantially as set forth.

20 3. In a toilet rack, the combination of a supporting bar, a shelf mounted on said bar, devices providing toothbrush receptacles on said shelf, and members on the bar for hanging corded cakes of soap, substantially as set forth.

25 4. In a toilet rack, the combination of a supporting bar, a shelf mounted on said bar, devices providing toothbrush receptacles on said shelf, and a plurality of pins outwardly

30 projecting from the bar for hanging corded cakes of soap, substantially as set forth.

35 5. In a toilet rack, the combination of a supporting bar, a sheet metal portion soldered on said bar and providing a shelf, and open-ended receptacles mounted on the shelf and adapted to hold toothbrushes, substantially as set forth.

40 6. In a toilet rack, the combination of a shelf, and a multi-pocketed receptacle for toothbrushes carried by a plate removably mounted on the shelf, said multi-receptacle adapted to be removed from position for the purpose of scalding, substantially as set forth.

45 7. In a toilet rack, the combination of a curved supporting bar adapted to be secured against a wall, a metal strip mounted on said bar providing a shelf and filling the space between the bar and said wall, and a plurality of open-ended receptacles mounted on the shelf and adapted to hold toothbrushes, substantially as set forth.

50 8. In a toilet rack, the combination of a curved supporting bar adapted to be secured to a wall, a shelf mounted on said bar and covering the space between the bar and the wall, a plurality of open-ended receptacles mounted on the shelf adjacent each end thereof, and a plurality of pins mounted on the bar and projected outwardly therefrom for hanging corded cakes of soap, substantially as set forth.

55 9. In a toilet rack, the combination of a bar, a shelf mounted thereon, a plate removably mounted on the shelf, a multi and open-

ended receptacle carried by said plate for holding toothbrushes, and a plurality of pins projecting outwardly from the bar for hanging corded cakes of soap, substantially as set forth.

70 In testimony whereof I have affixed my signature.

FRANK M. RINEHARDT.
